UNITED STATES PATENT OFFICE

162,025

PIPE WRENCH

Chauncey R. Hatch, Jr., Buffalo, N. Y.

Application October 27, 1950, Serial No. 12,759
Term of patent 14 years

(Cl. D54—16)

To all whom it may concern:

Be it known that I, Chauncey R. Hatch, Jr., a citizen of the United States, residing at Buffalo, State of New York, have invented a new, original, and ornamental Design for Pipe Wrench, of which the following is a specification, reference being had to the accompanying drawing, forming a part hereof.

Fig. 1 is a side elevation of a pipe wrench, showing my new design.

Fig. 2 is a top edge view of the wrench.

Fig. 3 is a cross section taken on line 3—3, Fig. 1.

Fig. 4 is a cross section taken on line 4—4, Fig. 1.

Fig. 5 is a cross section taken on line 5—5, Fig. 1, looking in the direction of the arrow crossing said line.

Fig. 6 is a cross section taken on line 6—6, Fig. 1.

Fig. 7 is a longitudinal section taken on line 7—7, Fig. 1.

Fig. 8 is a longitudinal section taken on line 8—8, Fig. 1.

I claim:

The ornamental design for a pipe wrench, as shown.

CHAUNCEY R. HATCH, JR.
